UNITED STATES PATENT OFFICE

149,669

DESIGN FOR AN EMBROIDERED TRIMMING

David L. Peister, New York, N. Y.

Application April 26, 1947, Serial No. 138,636

Term of patent 3½ years

(Cl. D92—1)

To all whom it may concern:

Be it known that I, David L. Peister, a citizen of the United States, residing in the city, county, and State of New York, have invented a new, original and ornamental Design for an Embroidered Trimming of which the following is a specification, reference being had to the accompanying drawing, forming a part thereof, in which the drawing shows a plan view of the front side of an embroidered trimming embodying my new design.

The rear side of the embroidered trimming is similar to the front side.

The embroidered trimming is shown against a black background to bring out the details of the design.

I claim:

The ornamental design for an embroidered trimming, as shown and described.

DAVID L. PEISTER.
